UNITED STATES PATENT OFFICE.

THOMAS TUCKER, OF MARSEILLES, ILLINOIS.

PAPER-STOCK REDUCING AND CONVEYING MACHINE.

1,359,638.

Specification of Letters Patent. Patented Nov. 23, 1920.

Application filed December 16, 1918. Serial No. 266,976.

To all whom it may concern:

Be it known that I, THOMAS TUCKER, a citizen of the United States, residing at Marseilles, in the county of La Salle and State 5 of Illinois, have invented a certain new and useful Improvement in Paper-Stock Reducing and Conveying Machines, of which the following is a full, clear, concise, and exact description, reference being had to the accompanying drawings, forming a part of 10 this specification.

This invention relates to improvements in paper stock reducing and conveying machine.

15 Heretofore, in the art of reducing paper stock to pulp used in the manufacture of paper-board, etc., the most common method of reducing the stock to the necessary degree of fineness has been by means of a tub 20 and beater roll wherein a quantity of the stock is introduced into the tub and continuously macerated and beaten until all of the stock is of sufficient fineness whereupon the beating engine is stopped and the reduced 25 stock removed and the process repeated for another quantity of stock. This method has proven slow and inefficient for the reason that it necessitates stopping the mechanism from time to time and, in addition, it is 30 evident that it is necessary to continue beating all of the stock until every portion thereof is reduced to pulp so that those portions of the stock which are sufficiently reduced in the early stages of the operation are 35 necessarily beaten and circulated thereafter.

More recently, so-called "continuous" methods of treating paper stock have been attempted to avoid the objections above noted. These later attempts, however, have 40 involved expensive attachments and complicated parts employed to effect by mechanical means the separation of the reduced stock from that insufficiently reduced. These arrangements, because of their complicated 45 nature, require constant attendance, frequently get out of order, thus necessitating shutting down of the mechanism, and in addition do not insure uniform extraction or separation of the reduced or half-stock from 50 the main body of stock in the tub.

The object of my invention is to provide an exceedingly simple, relatively inexpensive arrangement of beating engine and conveyor so arranged that those portions of the 55 stock which are sufficiently reduced, are im-

mediately extracted automatically from the body of the stock and conveyed from the beating engine.

Another object of my invention is to provide an arrangement of the type indicated in 60 the preceding paragraph which eliminates all mechanical means for effecting the separation of the stock.

Still another object of my invention is to provide an arrangement of the type above 65 indicated which may be readily applied as an attachment to the common form of beating engines now in use, at comparatively small expense with a resultant increased output.

The invention furthermore consists in the 70 improvements in the parts and devices and in the novel combinations of the parts and devices herein shown, described and made the subject matter of claim.

In the drawing forming a part of this 75 specification, Figure 1 is a top plan view of a paper stock reducing mechanism showing my improvements in connection therewith, the main portion of the hood over the beater 80 roll being removed and a portion of the screening element shown in section. Fig. 2 is a longitudinal, vertical, sectional view, taken substantially on the line 2-2 of Fig. 1. Fig. 3 is a sectional view, taken length- 85 wise of the beater roll and corresponding substantially to the line 3-3 of Fig. 2. And Fig. 4 is an enlarged, detail, sectional view illustrating more particularly the water flushing pipe and its relation with the ad- 90 jacent screen.

In said drawing, 10 denotes a tub of well known form having the usual midfeather 11 and heater roll 12. The beater roll 12 is carried by a shaft 13 mounted in bearings 95 14-14 that are preferably vertically adjustable, as by means of the hand wheels 15, in a well known manner. The tub is provided with a backfall 16 and the usual bed-plate 17 is employed to coöperate with the 100 beater roll 12. The parts above described are or may be of the usual construction.

Over the beater roll on one side thereof is disposed a hood 18, which may also be of the usual construction. Coöperable with the 105 beater roll 12 and arranged substantially concentric therewith, is a screen or perforated plate 19. The openings in the screen or plate are preferably of small diameter, and are disposed close together. Said plate 110

or screen 19 extends over an arc slightly less than a quadrant of the periphery of the roller and is preferably located diametrically opposite the backfall. In actual practice, said screen will be located about three or four inches away from the edges of the knives of the beater roll. At the lower end of the screen or plate 19 is disposed a preferably sheet metal trough 20 extending transversely of the tub and parallel to the axis of the beater roll, said trough 20 being extended to the farther side of the tub and having a discharge branch 21 adapted to convey the half-stock to a suitable receiving vat.

With the screen or plate 19 arranged as shown and described, it is evident that the paper stock will be thrown thereagainst by centrifugal force and due to the fact that the screen is substantially concentric with the roller, the discharge of the stock against the screen will be uniform throughout the area of the screen and thus prevent tendency of the stock to be unduly concentrated at any particular point on the screen. In this connection, it will, of course, be understood that the screen is coextensive in length with the length of the beater roll, as most clearly indicated in Fig. 1. As the stock is thrown against the screen, it is evident that those portions thereof which have been sufficiently reduced to pass through the relatively small perforations of the plate will pass through the holes and the insufficiently reduced stock will be automatically returned back to the beater tub for further reduction.

It is essential to keep the screen or plate 19 clean, or in other words, prevent it from becoming clogged and for this purpose, I preferably employ a curtain of water projected under pressure along the upper or outer surface of the perforated plate. To accomplish this, I dispose a water supply pipe 22 parallel with the axis of the beater roll and just above the highest point of the perforations in the plate 19. The pipe 22 is supplied by water under pressure from any suitable source and the water is forced from the pipe through a longitudinal slot 23 co-extensive with the length of the screen. As clearly shown in Figs. 2 and 4, I arrange the slot 23 so that the curtain or jets of water will be projected substantially tangential to the screen 19. The pipe 22 may be supported by any suitable means, as for instance, by a rod 24 having suitable pipe supporting clamps 25 thereon and in actual practice, the clamps 25 preferably have radially disposed, relatively narrow lips 26 extended into the slot 23. The lips 26 not only serve to hold the pipe against accidental rotative movement but also, by mounting the pipe and rod 24 so as to have relatively longitudinal movement, the lips 26 can be utilized to clean the slots 23 if

desired, without necessitating taking down any of the parts. On the outer side of the screen 19 I provide another section of hood, as indicated at 27, and at the top form the hood with a pivoted cover 28 arranged to permit easy access to the pipe and screen 19.

By employing the curtain or jets of water under pressure in conjunction with the perforated plate or screen 19, the water serves to flush or wash off of the upper side of the screen all those portions which have been projected through the perforations of the plate, or in other words, the half-stock or stock which has been sufficiently reduced to be passed onto the receiving vat. This half-stock is flushed down into the trough 20 and conducted off by the latter, as will be understood. Furthermore, the water projected from the pipe 22 automatically serves to flush out the holes or perforations of the screen and to wash back into the tub those portions of the stock which have not been sufficiently reduced to pass through the perforations and which have been caught on the under side of the screen 19. In other words, the curtain of water projected from the pipe 22 serves two distinct functions,—one the flushing of the reduced stock into the trough 20, and the other, the clearing out of the perforations and forcing back into the tub the insufficiently reduced stock.

In actual practice, the beater roll 12 will preferably be run in an elevated position for several hours so as to clear the bed plate by several inches and then for a relatively short time will be run in close relation with the bed plate so as to cut and reduce any string or other foreign substance not primarily reduced to the proper consistency. The operation proceeds continuously and the reduced pulp or half-stock is extracted or separated automatically and without the aid of any mechanical means for effecting the separation, the entire process depending upon the utilization of the water for flushing purposes. Actual practice has demonstrated that the arrangement is highly successful and increases the output of the reducing mechanism ten per cent. to fifty per cent., according to the character of the stock used, as compared with arrangements heretofore employed. Furthermore, because of the simplicity of my improvements, the same require a minimum of attention and do not ordinarily get out of order. It will also be evident that my improvements can be applied to the usual form of beating engines now employed with resultant increase in production, as well as to new beating engines.

Although I have herein shown and described what I now consider the preferred manner of carrying out my invention, the same is merely illustrative and I contem-

plate all changes and modifications that come within the scope of the claims appended hereto.

I claim:

5. 1. In an apparatus of the character described, the combination with a tub and beater roll, of means for screening the stock, said means being located adjacent the roll and against which the stock is adapted to be
10 thrown from the roll by centrifugal action; a pipe extending cross-wise of said screening means and to which water is adapted to be supplied under pressure, said pipe having a longitudinally extending slot thereon
15 through which the water is adapted to be projected in a curtain on to said screening means to thereby flush the latter; and means for supporting said pipe including an element having a finger extending into said
20 slot, said supporting means and pipe being adapted for relative movement whereby said slot may be cleared by said finger upon such relative movement.

2. In an apparatus of the character described; the combination with a tub and a beater roll; of means extending in an arc substantially concentric with said roll for screening stock thrown thereagainst by centrifugal action from the roll; and a pipe to
25 which water is adapted to be supplied under pressure, said pipe being disposed adjacent said screening means on the outer side thereof and near the top, said pipe having means for projecting water therefrom substantially tangential to the screening means.

3. In apparatus of the character described, the combination with a tub and beater roll, of a reticulated member arranged substantially concentric with the beater roll
40 and against which the stock is adapted to be thrown by centrifugal action with substantially uniform distribution thereover, and means for directing water onto the outer side of said member to thereby flush off from
45 said outer side those portions of the stock which are projected through the openings of said member.

4. In an apparatus of the character described, the combination with a tub and beater roll; of a perforated stock-grading screen, the screen being curved in cross section; and means for projecting a water spray tangential to said perforated screen on the

side thereof remote from the roll whereby the water so projected is adapted to simultaneously remove those portions of the stock passing through the screen to the outer side thereof and clear back from the inner side into the tub, those portions of the stock failing to pass through the screen.

5. In apparatus of the character described, the combination with a tub and beater roll; of a stock-grading screen above the tub and substantially concentric with the roll and extending over a relatively large arc of the periphery of the roll, said roll being adapted to throw the stock by centrifugal action against said screen with substantially uniform distribution thereover, and means for simultaneously removing those portions of the stock passing through the screen to the outer side thereof and clearing back from the inner side of the screen into the tub those portions of the stock failing to pass through the screen.

6. In apparatus of the character described, the combination with a beater roll, of a screen curved substantially concentric with the roll, a water supply pipe disposed adjacent said screen on the outer side thereof and having means for projecting water under pressure substantially tangential to said screen.

7. In apparatus of the character described, the combination with a tub and beater roll, of a perforated plate extending over a portion of the periphery of the roll and against which the stock is adapted to be projected by centrifugal force, a pipe adapted to be supplied with water under pressure and located on the outer side of said plate at the top of the perforations therein, said pipe being provided with a substantially continuous slot disposed to project a curtain of water along the outer surface of said perforated plate to flush the outer side thereof and force back into the tub those portions of the stock failing to pass through the perforations.

In witness that I claim the foregoing I have hereunto subscribed my name this 11th day of December, 1918.

THOMAS TUCKER.
